UNITED STATES PATENT OFFICE.

GEORGE S. MATTHEWS, OF KANSAS CITY, MISSOURI, ASSIGNOR OF ONE-HALF TO
AUGUSTINE DOEHLER, OF KANSAS CITY, MISSOURI.

SUSPENSION DEVICE.

1,170,084.

Specification of Letters Patent. Patented Feb. 1, 1916.

Application filed January 16, 1914. Serial No. 812,448.

To all whom it may concern:

Be it known that I, GEORGE S. MATTHEWS, a citizen of the United States, residing at Kansas City, in the county of Jackson and State of Missouri, have invented certain new and useful Improvements in Suspension Devices; and I do hereby declare the following to be a full, clear, and exact description of the invention, such as will enable others skilled in the art to which it appertains to make and use the same.

This invention is a suspension device for vehicles, having for its object to take up the shock or sustain jars transmitted to the body of the vehicle from the running gear thereof by supporting the body frame on resilient spherical devices, which permit of a cushion effect to the movement of the body, in substantially every direction, as distinguished from those devices which operate only in a vertical direction.

A further purpose is to provide an attachment which may be quickly and readily applied to a vehicle of ordinary construction at a minimum of cost.

In elastic suspensions previously known to me, it has been found necessary to employ inflatable devices or means which limit the action of the device to a vertical movement. In none of the devices with which I am familiar, are the attachments so constructed that they will permit of action in longitudinal and transverse lateral directions, as well as the vertical movement of a vehicle frame.

The invention is characterized by the plurality of resilient substantially spherical devices, each provided with a hollow core adapted to contain air at substantially atmospheric pressure. Each spherical device is positioned between a pair of opposed concave socket members which may be readily secured on a vehicle and so mounted that not all the weight placed on one of said socket members, such as an upper or inner one, is carried by the spherical device, but the longitudinal and lateral movements of said upper and inner sockets and their supporting members are opposed in all directions by the lower member, said lower member limiting the vertical movement of the upper member.

The attachment may be employed in connection with the inner springs of a vehicle, or the springs may be omitted, as well as

the pneumatic or resilient tires from the 55 wheels.

Several embodiments of the invention are illustrated in the accompanying drawings, although it is to be understood that the constructions shown therein are for the purposes of illustration only, and not as defining the limits of the invention.

In the drawings—Figure 1 is a plan view of a vehicle frame, parts being broken away. Fig. 2 is an end view of the frame illustrating the manner of application of the device thereto. Fig. 3 is a side elevation of the device illustrated in Figs. 1 and 2. Fig. 4 is an enlarged detail side elevation of a pair of socket members with the resilient member in position. Fig. 5 is an enlarged sectional view through the device of Fig. 4, the section being taken on the line *a—a* of Fig. 1. Fig. 6 is a side elevation illustrating the device applied to half elliptic springs. Fig. 7 is a side elevation showing a device connected with platform springs, the sockets being connected at each end of the side springs. Fig. 8 is a rear elevation of the device connected to platform springs. Fig. 9 is a side elevation showing the device connected directly with the frame and axle, the springs being omitted therefrom, and Fig. 10 is a side elevation of a device applied to the lower portion between full elliptic springs 85 and the axle.

Referring more particularly to the embodiment of the invention illustrated in Figs. 1 to 5, the frame of the vehicle, such as an automobile frame or chassis, is illustrated 90 at 1 and may be of any desired form, and may be mounted upon any preferred type of spring.

The invention preferably comprises a plurality of complementary members each shown in the form of sockets, the inner socket member 2 being preferably positioned on a plane slightly above that of its complementary outer socket member 3. The inner socket member 2 is preferably secured to the frame 1 in 100 any suitable manner, and in the drawings this member 2 is shown provided with parallel arms 4 which serve as means for supporting the member on the frame 1. Any suitable devices (not shown), may be employed 105 to clamp the arms 4 to the frame member 1.

The outer socket member 3 may be secured to the springs, which are indicated at

5 in Figs. 1, 2 and 3. These outer members 3 may be provided with depending lugs 6 to serve as means to retain the member 3 in a predetermined position with relation to 10 the socket member 2, and any suitable fastening device (not shown), may be employed in connection with these lugs 6 to retain said member 3 in position. The member 2 is illustrated as having a substantially 15 rectangular outer body, with a portion of its inner face concaved, the concave portion being such as to receive less than half of the spherical body adapted to fit therein, as will be understood from Figs. 4 and 5. The 20 edges of the member 2 adjacent the concaved portion, are preferably curved inwardly as at 7, along two sides thereof, but are substantially rectangular, for example, at the top and bottom in Fig. 1, with curved 25 corners along the other two sides thereof. The member 3 is formed with a concave portion 8 substantially similar to the concave portion of the member 2, to receive the spherical body, and this lower member is 30 also provided with two sides of its substantially rectangular body, cut away at 9 on an arcuate line at the top face thereof, similar to the cut away portion 7 of the socket member 2, as illustrated in Fig. 1. The 35 face opposite to this portion 9, or the bottom face thereof, is preferably extended beyond the vertical plane of the top face, as in Fig. 5, to serve as a support for the resilient member 10 to be housed between said socket 40 members 2 and 3. The side sections 11 are preferably rectangular except for the corner 12 thereof (Fig. 2), which registers with the inwardly curved portion 7 of the upper member. The lower member 3 may be provided 45 also with an upwardly extending angular arm 13, terminating in a housing 14 which is adapted to be positioned in alignment with an extended arm 15 of the upper socket member 2. The lower surface of this 50 housing 14, which is on a plane with the horizontal arm 16 of the lower member, is preferably arranged at a predetermined point above the arm 15 of member 2, to permit of a limited vertical movement of member 2 with reference to member 3, or 55 vice versa. Cushioning the action or impact of the arm 16 of housing 14 upon the arm 15, there may be provided a coil spring 17 mounted within the housing 14, and bearing 60 at all times upon the upper surface of the arm 15.

The resilient member 10 is preferably spherical in form and provided with a hollow core 18 as illustrated in Fig. 5, it being 65 found preferable to confine air at atmospheric pressure within said core. This spherical member is adapted to rest within the concave portions of the socket members 2 and 3 to permit of rotative movement therein.

65 The resilient spherical member 10 serves to

70 maintain the socket members 2 and 3 apart, and the peculiar formation of the opposed edges of the socket members 2 and 3, together with the position in which these members are placed upon the frame and running gear, causes an irregular path to be formed substantially around the spherical member 10, as indicated at *x* in the various views. This feature is obtained also by the mounting of the member 2 on the frame, out of the 75 longitudinal plane of the member 3, and also substantially out of the vertical plane of said member, as also understood by reference to Figs. 1, 2 and 3.

The device may be employed between the 80 body frame 1 and the axle 19, as shown in Fig. 9, or it may be positioned between the axle 19 and the springs, as shown in Fig. 10, or it may be applied between the frame 1 and the springs 20, as shown in Figs. 6, 85 7 and 8.

It will be noted that the invention comprises but few parts, can be readily adapted to any road vehicle, is susceptible to quick and easier manufacture in the event of accident, and is capable of resisting or absorbing the sudden jolt or shocks in not only 90 vertical directions, but also longitudinal and lateral directions.

Having thus described the invention, what 95 I claim as new and desire to secure by Letters Patent is:—

1. In a suspension device for vehicles, a plurality of complementary socket members, each having a concave face, one of said members being carried by the frame of the vehicle, the other of said members being mounted slightly below the horizontal plane and substantially cut off alignment with said first named member, and a spherical resilient device housed between said concave faces to separate said socket members and permit of free rotative movement of the resilient device between said socket members.

2. In a suspension device for road vehicles, a plurality of upper and lower socket members, a substantially spherical resilient device adapted to be interposed between said socket members to maintain said members out of contact with each other, and means carried by the lower member to engage the upper member to permit limited universal movement of the upper socket member with relation to the lower socket member.

3. In a device of the class described, complementary socket members each having a concave face at substantially the side thereof, said members being arranged to house a substantially resilient spherical device which operates to maintain said socket members in their separated positions, the socket members being so positioned with relation to each other that the spherical device may be rotated within the socket.

4. In a device of the class described, a

- plurality of complemental socket members, some of which are adapted to be mounted upon the running gear of the vehicle, while other socket members are adapted to be 5 mounted upon the vehicle frame, the frame socket members being positioned out of vertical alinement with the running gear socket members, and a substantially spherical resilient device interposed between each pair 10 of the socket members to maintain them out of contact with each other, whereby the movement of the socket members is opposed by the resilient members in substantially all directions.
- 15 5. A suspension device comprising a plurality of complemental socket members each having a concave face and one side substantially cut away, a resilient spherical member separating the socket members, said 20 socket members when in operative position with relation to each other leaving an irregular space between them and completely around the spherical member.
6. A suspension device comprising a plurality of complemental socket members each 25 having a concave face, said members being so mounted that a part of one member is out of vertical alinement with a part of its co-operating socket member, and a resilient 30 spherical member separating the socket members, said socket members being so positioned with relation to each other as to form an arcuate space between the socket members around the spherical member to permit 35 of movement of the opposed socket members in a plurality of directions.
7. A suspension device comprising an upper socket member having a forwardly inclined extension and a concave portion, the 40 edges of the socket member adjacent the concave portion being curved for a portion thereof, a lower socket member having a concave portion, the edges of the socket member adjacent the concave portion being 45 partly straight and partly curved to register with the curved portion of the upper socket member, and a spherical resilient member adapted to rest within the concave portions and between the two socket members to retain 50 said members out of engagement, such resilient member operating to maintain an irregular space between the upper and lower socket members.
8. A suspension device comprising an 55 upper socket member having a forwardly inclined extension and a concave portion, a lower socket member provided with a con-
- cave portion and an upwardly extended arm, a housing carried by said arm in substantially vertical alinement with a portion of 60 said upper socket member, resilient means positioned within the housing and adapted to engage a portion of the upper socket member, and a resilient member mounted between said socket members to maintain a 65 space between them.
9. In a suspension device for vehicles, the combination with a vehicle frame and the running gear, of a plurality of socket members carried by each side of the frame, the 70 socket members on each side having reversely positioned concave faces, a plurality of socket members carried by the running gear and positioned on a plane below the 75 socket members of the frame, said running gear sockets having facing concave portions adapted to register with the oppositely positioned concave portions of the running gear socket members, and a spherical resilient member adapted to be positioned for rotatable movement between each pair of said 80 frame socket members and running gear socket members to leave a space between them.
10. In a suspension device for road vehicles, a plurality of complemental socket members each having a concave face, and with irregular edges, one edge of the member forming a substantially ogee curve, and a spherical member interposed between said 90 socket members to be housed by the concave faces, said members being so mounted on a vehicle as to leave an irregular space between them substantially all around the 95 socket member, said space being diagonal to the horizontal and vertical planes of the vehicle frame.
11. A suspension device comprising an upper socket member having a concave face angularly positioned with relation to the 100 member, a lower socket member having an upwardly directed concave portion, a spherical hollow resilient element adapted to be housed between said upper and lower socket members to maintain said members out of 105 contact to permit rotative movement of the resilient element between the socket members.

In testimony whereof, I affix my signature, in presence of two witnesses.
